LOOM HARNESS

John J. Kaufmann, Elkins Park, Pa., assignor to
Steel Heddle Manufacturing Company, Philadelphia, Pa., a corporation of Pennsylvania

Application August 31, 1949, Serial No. 113,429

15 Claims. (Cl. 139—92)

1

This invention relates to loom harness, and it relates more particularly to the construction and arrangement of the top and bottom rails of the harness frames commonly employed in looms, in which frames the heddles are mounted for the purpose of forming the successive sheds of the warp threads during the weaving operation.

In the loom harness frames at present in common use, the top and bottom rails or shafts are usually made of wood, as such material has the desired physical characteristics and permits the easy mounting of the "hardware" and the securing of the other parts of the frame which are attached thereto.

Recently, it has been proposed to make the top and bottom rails of extruded aluminum or magnesium alloy shapes, but in the use of such material certain other difficulties have arisen, which however, it is not necessary to discuss.

The principal object of the present invention is to provide a loom harness frame in which the top and bottom rails are made of a composite form, with the main or body portions thereof made of wood having its inner and outer edges reinforced by a strip of aluminum or magnesium alloy of desired shape in cross-section which may be readily made by the extrusion process.

A further object of the invention is to provide a loom harness frame of the character aforesaid in which the top and bottom rails may be inexpensively made and which will be of considerably greater strength than those made entirely of wood.

A further object of the invention is to provide a loom harness frame having top and bottom rails of the character aforesaid which will permit the other parts of the frame to be readily and securely attached thereto.

A further object of the invention is to provide a loom harness frame having top and bottom rails of the character aforesaid in which the "hardware" commonly used in such frames may be readily and conveniently mounted therein, as for example, the hooks or eyes for attaching the actuating cords or straps to the rails of the frame, and also the so-called "hooks" on the inner edges of the rails which serve to support the heddle rods in the frame intermediate the ends thereof.

The nature and characteristic features of the present invention will be more readily understood from the following description, taken in connection with the accompanying drawing forming part hereof, in which:

2

Figure 1 is a side elevation of a loom harness frame embodying the main features of the present invention.

Fig. 2 is a transverse sectional view, enlarged, of one of the rails, the section being taken on the line 2—2 of Fig. 1;

Fig. 3 is a similar view, the section being taken on the line 3—3 of Fig. 1, illustrating the manner of securing the reinforcing members to the body portion of the rail;

Fig. 4 is a similar view, the section being taken on the line 4—4 of Fig. 1, showing the manner of mounting in the frame a "hook" for the purpose of supporting one of the heddle rods intermediate the ends thereof;

Fig. 5 is a similar view, the section being taken on the line 5—5 of Fig. 1, illustrating the mounting on the rail of one of the hook members for securing the actuating cords or straps to the frame;

Fig. 6 is a similar view illustrating the use of a screw eye for the same purpose as the hooks shown in Figs. 1 and 5; and

Fig. 7 is an enlarged cross-sectional view of a portion of one of the rails with one of the reinforcing members attached thereto by means of an adhesive.

It should, of course, be understood that the description and drawing herein are illustrative merely, and that various changes and modifications may be made in the structure disclosed without departing from the spirit of the invention.

Referring to the drawing, in the particular embodiment of the invention therein shown, the heddle frame comprises the usual components of top and bottom rails 10, connected at their ends by end struts 11, heddle supporting rods 12 located near the inner edges of the top and bottom rails, respectively, and heddles 13 of any preferred type mounted on said rods 12.

The present invention relates more particularly to the construction and formation of the top and bottom rails 10. Each of said rails, as shown in cross-section in Fig. 2 of the drawing, comprises a central body portion 14 made of wood reinforced along its top and bottom edges by reinforcing strips 15. The reinforcing strips 15 are preferably made of an extruded shape of one of the lighter alloys, of aluminum or magnesium, which are now available.

Each strip 15 has a transverse portion 16 and two side walls 17, the inner face of each of the side walls 17 of the reinforcing strip 15 being inclined, as at 18, with respect to the vertical

central axis of the cross-section, thereby to provide between said faces an internal tapered groove or recess running from end to end of the strip. Each marginal part of the body portion 14 of the rail is shaped complementally to the internal groove of the strip 15 so as to snugly fit in said groove.

The outer faces of the side walls 17 of the reinforcing strip are preferably parallel and flush with the side faces of the wooden body portion 14 of the rail. The transverse or horizontal portion of the reinforcing strip is provided with a longitudinal V-shaped groove 19 running from end to end for a purpose to be presently explained. The outer corners of the reinforcing strip are preferably rounded as at 20 for the purpose of minimizing any tendency of the rails of adjacent frames to ride over each other when the shedding action takes place.

In the mounting of the various parts and attachments to the rail, as well as the placing of the securing screws, no great degree of accuracy is required in the lengthwise location of such devices, but it is important, however, that the same be properly centered transversely with respect to the rail, as otherwise there will be a tendency of the threaded shank portions of such devices to extend through the sides of the body of the rail. With the foregoing in mind, the central longitudinal V-shaped groove 19 has been provided, which will effectively serve as a means for centering the drills which are used to make the holes for the threaded shanks of the various parts, preliminarily to the mounting of the same in the rails, for example, the fastening screws 21, the screws 22 for securing the end struts 11, and the various other devices, such as the attachment hooks 23 or eyes 24 for the actuating straps or cords not shown, and also for the hooks 25 for supporting the heddle rods 12 intermediate their ends.

The longitudinal groove 19 will also serve as a means for preventing undesired turning of the hooks 23 or eyes 24 after the same are mounted in position, as such devices are usually provided with tits 26 which will seat themselves in the grooves 19 when the hooks or eyes are screwed into the rails to their innermost limit positions.

In lieu of the fastening screws 21, or in addition thereto, the reinforcing member 17 may be secured to the rail 10 by means of an adhesive 27. Any of the adhesives which are now freely available in the market for effectively securing metal to wood may be used for this purpose, as shown in Fig. 7 of the drawings. A discussion of such adhesives may be found on page 21 of the July 1947 issue of "Plastics," a copy of which is available in Division 33 of the U. S. Patent Office.

The rails 18 of a harness frame, when constructed as aforesaid, and after the various attaching screws and other devices are mounted therein, will be found to be greatly strengthened and stiffened, as the reinforcing strips are located at the places of greatest strain of the top and bottom rails, and the same will greatly lengthen the life of the harness frame.

I claim:

1. A loom harness frame having top and bottom rails, the top and bottom edges of which have reinforcing members mounted thereon, said reinforcing members each comprising a metallic strip having an internal groove extending from end to end and in which a complementally shaped edge portion of the body of the rail is seated.

2. A loom harness frame having top and

bottom rails, the top and bottom edges of which have reinforcing members mounted thereon, said reinforcing members each comprising a metallic strip having a groove extending from end to end tapered in cross-section and in which a complementally shaped edge portion of the body of the rail is seated.

3. A loom harness frame having top and bottom rails the main or body portions of which are made of wood with reinforcing members mounted on the top and bottom edges thereof, said reinforcing members each comprising a metallic strip having a groove extending from end to end tapered in cross-section and in which a complementally shaped edge portion of the body of the rail is seated.

4. A loom harness frame having top and bottom rails the main or body portions of which are made of wood with reinforcing members mounted on the top and bottom edges thereof, said reinforcing members each comprising a metallic strip having a groove extending from end to end tapered in cross-section and in which a complementally shaped edge portion of the body of the rail is seated, and the side faces of said reinforcing strip being substantially flush with the side faces of the body portion of the rail.

5. A loom harness frame having top and bottom rails the main or body portions of which are made of wood with reinforcing members mounted on the top and bottom edges thereof, said reinforcing members each comprising a metallic strip having an internal groove extending from end to end tapered in cross-section and in which a complementally shaped edge portion of the body of the rail is seated, the side faces of said reinforcing strip being substantially flush with the side faces of the body portion of the rail, and the reinforcing strip having on its external face a central V-shaped longitudinal groove extending from end to end thereof.

6. A loom harness frame having top and bottom rails, the top and bottom edges of which have reinforcing members mounted thereon, said reinforcing members each comprising a metallic strip having on its external face a central V-shaped longitudinal groove extending from end to end thereof.

7. A loom harness frame having top and bottom rails, the top and bottom edges of which have reinforcing members mounted thereon, said reinforcing members each comprising a metallic strip having an internal groove extending from end to end and in which a complementally shaped edge portion of the body of the rail is seated, and the reinforcing strip having on its external face a central V-shaped longitudinal groove extending from end to end thereof.

8. A loom harness frame having top and bottom rails, the top and bottom edges of which have reinforcing members mounted thereon, said reinforcing members each comprising a metallic strip having an internal groove extending from end to end tapered in cross-section and in which a complementally shaped edge portion of the body of the rail is seated, and the reinforcing strip having on its external face a central V-shaped longitudinal groove extending from end to end thereof.

9. A loom harness frame having top and bottom rails, the main or body portions of which are made of wood with reinforcing members mounted on the top and bottom edges thereof, said reinforcing members each comprising a metallic strip having an internal groove extending from end to

end tapered in cross-section and in which a complementally shaped edge portion of the body of the rail is seated, and the reinforcing strip having on its external face a central V-shaped longitudinal groove extending from end to end thereof.

10. A loom harness frame having top and bottom rails, the main or body portions of which are made of wood with a reinforcing member mounted on at least one of the edges thereof, said reinforcing member comprising a metallic strip having a groove in which a complementally shaped edge portion of the body of the rail is seated, the reinforcing strip being secured to said edge portion of the rail by an adhesive.

11. A loom harness frame having top and bottom rails, the main or body portions of which are made of wood with a reinforcing member mounted on at least one of the edges thereof, said reinforcing member comprising a metallic strip having an internal groove tapered in cross-section in which a complementally shaped edge portion of the body of the rail is seated, the reinforcing strip being secured to said edge portion of the rail by an adhesive.

12. A loom harness frame having top and bottom rails, the main or body portions of which are made of wood with reinforcing members mounted on the top and bottom edges thereof, said reinforcing members each comprising a metallic strip having an internal groove tapered in cross-section and extending from end to end and in which a complementally shaped edge portion of the body of the rail is seated, the reinforcing strips being secured to the wooden body portion by an adhesive.

13. A reinforcing member for the edges of the rails of loom harness frames comprising a metallic strip having an internal groove extending from end to end, said groove being of tapered cross-section and in which a complementally shaped edge portion of the body of the rail is adapted to be seated.

14. A reinforcing member for the edges of the rails of loom harness frames comprising a metallic strip having an internal groove extending from end to end and in which a complementally shaped edge portion of the body of the rail is adapted to be seated, and said reinforcing strip having, on the external face thereof which is opposite the internal groove, a central longitudinal groove extending from end to end thereof.

15. A reinforcing member for the edges of the rails of loom harness frames comprising a metallic strip having an internal groove extending from end to end, said groove being of tapered cross-section and in which a complementally shaped edge portion of the body of the rail is adapted to be seated, and said reinforcing strip having, on the external face thereof which is opposite the internal groove, a central V-shaped longitudinal groove extending from end to end thereof.
